United States Patent Office.

HENRY H. PALMER, OF ROCKFORD, ILLINOIS.

Letters Patent No. 84,300, dated November 24, 1868.

IMPROVED SPRING-BED BOTTOM.

The Schedule referred to in these Letters Patent and making part of the same.

To all whom it may concern:

Be it known that I, HENRY H. PALMER, of Rockford, in the county of Winnebago, and State of Illinois, have invented a new and improved Spring-Bed Bottom; and I do hereby declare that the following is a full and exact description of the same, reference being had to the accompanying drawings, and to the letters of reference marked thereon.

This invention relates to certain improvements in spring-bed bottoms; and consists principally in a novel combination and arrangement of parts, which are believed to be old in themselves, by means of which a durable and desirable bed-bottom is obtained, as will be fully described hereinafter.

In the drawings—

Figure 1 represents a plan view of my improved bed-bottom;

Figure 2, a side elevation, a portion being broken away, to show the springs; and

Figure 3, a view of the same, with the springs depressed as when in use.

The same letters refer to identical parts in all the drawings.

To enable those skilled in the art to make and use my invention, I will now proceed to describe its construction and operation.

A represents a rectangular frame, which may be constructed of any desired size.

c represent slats, of the usual construction, to the ends of which are attached the single or forked straps B, which latter may be made of leather or any other suitable flexible material. These straps are caught over hooks or pins upon the head or foot-pieces, as shown.

F represent springs, resting upon the cross-pieces E E, and securely attached thereto, in the usual manner.

Their upper ends bear against the slats c c, and are held securely in position by the projections G upon the under sides of the slats, as clearly shown in fig. 2.

D is a flexible or elastic cord, attached to the sides of the frame, and passing over the slats, being secured to each of the latter in a proper manner.

By the combination and arrangement herein described, certain advantages are secured over most spring-bottoms in use, some of which may be enumerated, as follows:

All end-play is prevented by means of the stops B. This is a serious objection to bottoms in which the ends of the slats are not secured.

All side-play is prevented by means of the band D.

While all end and side-play is prevented, yet any portion of the bed will yield readily to the pressure of the body, without affecting the other parts of the bed, as is the case when the slats are rigidly connected together.

The whole bottom is secure, and may be walked upon, as is sometimes necessary, without either injury to the bottom or to the person who walks.

By the arrangement of the straps B, the slats are made high in the middle, so that when the bed is occupied, and the springs are depressed, the occupant will lie perfectly straight.

I am well aware that most if not all of the parts of my invention are old, but the combination is believed to be entirely new, and by it a most desirable bed-bottom is obtained.

Having thus fully described my invention,

What I claim, and desire to secure by Letters Patent of the United States, is—

The bed-bottom described, consisting of the frame A with cross-pieces E, slats c with straps B and projections G, springs F and band D, the whole being combined and arranged as and for the purpose set forth.

HENRY H. PALMER.
